UNITED STATES PATENT OFFICE

138,740

DESIGN FOR AN ALPHABET

Ceola P. Hayes, Santa Monica, Calif.

Application January 29, 1944, Serial No. 112,367

Term of patent 3½ years

(Cl. D64—14)

To all whom it may concern:

Be it known that I, Ceola P. Hayes, a citizen of the United States, residing at Santa Monica, in the county of Los Angeles and State of California, have invented a new, original, and ornamental Design for an Alphabet, of which the following is a specification, reference being had to the accompanying drawing, forming part thereof.

The drawing is a plan view of an alphabet showing my new design.

I claim:

The ornamental design for an alphabet, as shown.

CEOLA P. HAYES.
